ILLINOIS.

ARCH-PLATE FOR FURNACES.

1,019,035.

Specification of Letters Patent.

Patented Mar. 5, 1912.

Application filed July 16, 1908. Serial No. 443,756.

To all whom it may concern:

Be it known that we, JOHN R. FORTUNE and FRANK B. BIGELOW, citizens of the United States of America, residing at Detroit, in the county of Wayne and State of Michigan, and Chicago, Cook county, Illinois, respectively, have invented certain new and useful Improvements in Arch-Plates for Furnaces, of which the following is a specification, reference being had therein to the accompanying drawings.

In automatic furnaces in which a casting or so-called arch-plate is employed to support the furnace-arch and to form one side of the coal magazine it is found that these plates by being subjected to the extreme heat become in time burned out, cracked or warped so that it is necessary to remove and replace them. Numerous forms of arch-plates have been devised, some being cast with a series of ribs forming air passages through which a circulation of air is maintained to cool the plate but it has been found that, notwithstanding the air circulation, the lower end of the plate which is subjected to a very high temperature will, in time, become warped, cracked or burned so that it is necessary to remove and discard the whole arch-plate and that it has also been found that arch-plates so formed are expensive, being difficult to cast, and requiring complicated cores.

The object of this invention is to provide an arch-plate having air passages and so constructed that it may be easily and cheaply made and is formed in detachable sections so that if damaged by the heat, the damaged section may be removed and a new one put in its place, obviating the necessity for removing and discarding the entire arch-plate.

To this end the invention consists in the construction substantially as shown and described and particularly pointed out in the claims, reference being had to the accompanying drawings in which:

Figure 1 is a perspective view of a portion of a furnace showing an arch-plate embodying the invention, in place therein; Fig. 2 is a diagrammatic view showing a furnace in transverse section; Fig. 3 is an enlarged perspective detail of an arch-plate with one of the removable sections detached; and Fig. 4 is a transverse section of the same.

As shown in the drawings 1 are the in-

clined grate-bars supported at their lower ends upon the grate-bearer 2 with their upper ends resting against the coking-plates 3 over which the coal from the magazines 4 above, is shoved by the stoker-boxes 5 actuated by segments on the rock-shafts 6, all being constructed and arranged in the usual manner.

The inner sides of the coal magazines 4 are formed by the arch-plates 7 embodying this invention. This arch-plate is preferably cast with a vertical wall 8 having on its inner side an inwardly extending longitudinal rib 9 and a series of webs 10 at the upper side of said rib connecting the wall and rib 70 to brace the latter and form a series of pockets 11 at its upper side, said webs being given such a slant that when the pockets formed between are filled with cement or other suitable material level with the slanting upper edges of the webs, a ledge or skew seat of the desired inclination will be formed thereby, to support the end of the upper or outer arch 12 of the furnace.

Adjacent to the lower edge of the wall 8 is a series of spaced inwardly extending ears 13 having horizontal, laterally extending lugs or pins 14 and for the purpose of strength and to prevent warping, webs 15 connect said ears and rib 9 and said webs 15 are intermediately connected by a longitudinal rib 16. The lower edge of the wall 8 is extended inwardly and downwardly to form a shelf or ledge 17 extending at the proper inclination to support a series of sections 18 at the desired angle to form a skew seat or abutment for the lower or inner arch 22 of the furnace. The inwardly extending ledge and the several spaces between the ears 13 form a series of pockets into which the several sections loosely fit and are held by their own weight which tends to turn them upon their pins 14. Each of these sections 18 are formed with an upper side or wall provided with an upwardly extending rib or projection 19 to engage the fire-brick of the arch and hold the same in place thereon, and integral with the inner or lower surface of this wall is a series of ribs 20 which form between them air passages 21 opening through the inner end of the section. At the opposite end of the section the upper wall and said ribs are turned upward forming a hooked end to engage beneath the pins 14 on the ears and loosely interlock the section 110.

with the supporting wall 8. Each section fits loosely between the ears 13 and is cut away at its lower side to receive the shelf 17, the ribs 20 engaging at their lower edges 5 said shelf and wall 8 and forming air passages opening at their upper ends beneath the rib 16 into the space between the arches of the furnace. These sections thus form hollow twyers between the spaces above and 10 below the arch and they fit loosely together and against the ears and adjacent parts, their upper surface forming a continuous seat for the inner arch. The air passages, when the sections are in place, are open at 15 their ends only, their upper ends opening just below the rib 16 and their lower ends through the lower ends of the sections, and thus liability to their becoming clogged with cement or other material during the construction of the arches, is obviated.

The lower portion, or lower arch-seat of the arch-plate is subjected to the greatest heat and is, therefore, the part which is the most liable to be injured thereby. By making this portion of the arch-plate in detachable sections, if any portion of it becomes burned or cracked, that portion or section may be readily removed and a new section put in its place without the necessity for rehewing the entire arch-plate and liability to warping and cracking due to expansion and contraction, is eliminated, by loosely engaging the sections with their support and by providing space between the sections sufficient to allow for such expansion. These sections may also be much more cheaply cast with air passages, than ribs forming air passages, can be cast as an integral part of the whole plate, and by making the main 30 body of the arch-plate in the form described, it may also be cheaply cast, thus greatly cheapening the whole construction of the arch-plate.

Having thus fully described our invention 45 what we claim is:

1. An arch plate for automatic stokers comprising a supporting wall, and an arch seat member extending outwardly from said wall and held by gravity, loosely interlocked 50 therewith.

2. An arch-plate comprising a supporting member, a series of members together forming a continuous arch seat, and means for detachably securing said members to the 55 supporting member, said arch plate being formed with air passages between said series of members and said member.

3. An arch-plate comprising a supporting member and a series of members detachably 60 attached to the supporting member, each having a continuous imperforate upper side which sides conjointly form an arch seat and said members being formed with air passages below said side extending upward between said members and said supporting

member and opening at one end along the lower longitudinal edge of said members and at their opposite ends between the upper edges of said members and said supporting member, above the arch seat.

4. An arch-plate comprising a supporting member, a series of members each having a continuous upper surface, said surfaces together forming an arch seat, ribs on said members forming air passages between said members and said supporting member, and means for attaching the said members to said supporting member.

5. An arch-plate comprising a supporting member, a plurality of members having curved ends, means on the supporting member with which said ends are adapted to be engaged to detachably attach said members to said supporting member, and ribs on said ends engaging the supporting member and forming air passages between said ends and said member.

6. An arch-plate consisting of a wall provided with a series of pockets at one side having upper edges inclined relatively to the 90 wall and adapted to receive material to form a skew seat for an arch.

7. An arch-plate consisting of a wall, a rib extending laterally from said wall, and a series of webs connecting the rib and wall 95 at the upper side of said rib to form a series of pockets adapted to receive a material to form a seat for an arch.

8. An arch-plate consisting of a wall, a rib extending outward from one side of said 100 wall and a series of parallel webs at the upper side of said rib formed integral therewith and with said wall and having straight outer edges extending at an inclination to the wall, said webs forming pockets between them adapted to be filled with a material level with their upper edges to form a seat for an arch.

9. An arch-plate comprising a vertical wall, a shelf on the lower edge of said wall 110 extending outward therefrom, a series of members supported by said shelf having imperforate upper sides together forming an arch seat, said members being also provided with air passages between said shelf and wall and said members, and means on the wall for engaging said members and detachably holding the same in place upon said shelf.

10. An arch-plate comprising a vertical wall having a projecting portion, a series of spaced ears on said wall near said projecting portion, a series of members fitting between said ears and seating upon the projecting portion of the wall, and means on the ears engaging the members to detachably hold the same in place.

11. An arch-plate consisting of a wall, an inclined shelf upon the lower edge of said wall, a series of detachable sections 130

having cut-away portions to receive the shelf and provided with air passages extending therethrough, said shelf forming a part of the lower wall of said passages, and 5 means on the wall for engaging and detachably holding the sections.

12. An arch plate comprising a wall, a shelf on the lower edge of said wall, a series of spaced ears on the wall each having 10 a laterally projecting member, and a series of members resting upon said shelf and together forming an arch seat, said members being formed with curved ends to engage the laterally extending members on the ears.
13. An arch-plate consisting of a wall, an inclined shelf at the lower end of said wall, a series of ears extending outward from said wall adjacent to the shelf, laterally extending pins on said ears, and a series of 20 sections to fit between the ears and rest upon the shelf, said sections each having a curved end engaging beneath the pins and each formed with a series of air passages opening through the lower ends of said sections and upward through the curved ends of said sections between said ears adjacent to the wall.

14. An arch-plate consisting of a wall, a rib extending laterally from one side of 30 said wall, webs connecting the rib and wall at the upper side of said rib to form a series of pockets, a series of laterally extending ears adjacent to the lower edge of said wall, webs connecting said ears and rib, pins on 35 the ears, an inclined shelf on the lower edge of the wall, a series of sections adapted to fit between the ears and rest upon the shelf and provided with a curved end to engage beneath the pins and each formed with a series of air passages opening through its 40 lower end and through the upwardly curved upper end adjacent to the wall.

15. An arch-plate for automatic stokers comprising a wall extending the length of 45 the arch-plate, and a series of members loosely engaged with and independently supported by said wall and extending laterally therefrom, said members conjointly forming a seat for an arch.

50 16. An arch-plate for automatic stokers comprising a vertical wall, a series of members supported by said wall and extending laterally therefrom, said members conjointly forming a continuous seat for an arch, and interlocking means for loosely attaching said members to said wall.

17. An arch-plate comprising a wall extending the length thereof, a series of members detachably attached to the wall and arranged in alinement to conjointly form an arch seat along one side of said wall, said

members being formed with ribs at one side adjacent to said wall forming air passages between said members and wall, and means for detachably attaching said members to the wall.

18. In a furnace, the combination with a magazine, an arch abutment, supported by said magazine and loosely interlocked therewith so that there may be relative 70 movement between the magazine and the abutment, and an arch supported upon said abutment.

19. In a furnace, the combination with a magazine, an arch abutment supported by 75 said magazine, and loosely interlocked therewith to permit relative movement between the magazine and abutment, and an arch supported upon said abutment, said abutment being provided with a passage 80 constituting a twyer between the space above and the space below said arch.

20. In a furnace, the combination with a magazine, of an arch abutment loosely interlocked with the side wall thereof, and extending outwardly therefrom, the weight of said abutment maintaining the same in interlocked engagement with the magazine wall, and an arch supported upon said abutment. 90

21. In a furnace, the combination with a refractory arch, a fuel magazine at one side thereof, said magazine being provided with a vertical side wall having a ledge extending laterally from the outer surface thereof, an arch abutment seated on said ledge, and provided with an upwardly extending portion, and a keeper on the side wall of the magazine for loosely engaging said portion. 95

22. In a furnace, the combination with a 100 magazine having a wall provided with a plurality of pockets, a plurality of independent arch abutments supported in said pockets and each loosely interlocked therewith so that there may be relative movement between the magazine and the abutments, the abutments being arranged end to end and in close proximity to each other, thereby forming a substantially continuous arch seat. 105
